UNITED STATES PATENT OFFICE.

DONALD W. LANG AND ARTHUR D. VAUGHN, OF ELDRED, PENNSYLVANIA.

SPARK-PLUG.

1,353,597.

Specification of Letters Patent. Patented Sept. 21, 1920.

Application filed May 19, 1919. Serial No. 298,093.

To all whom it may concern:

Be it known that we, DONALD W. LANG and ARTHUR D. VAUGHN, citizens of the United States, residing at Eldred, in the county of McKean and State of Pennsylvania, have invented certain new and useful Improvements in Spark-Plugs, of which the following is a specification.

This invention has for its object to provide a spark plug for explosive engines embodying such novel features of construction as to afford adjustment of one of the electrodes whereby the length of the spark gap may be varied according to the intensity of the current of the ignition system.

Another object is the provision of an indicator associated with the relatively adjustable electrode by which the length of the spark gap may be readily determined and varied and which, in addition, constitutes a retaining means for maintaining the relatively adjustable electrode in adjusted position.

With the above and other objects in view, as will appear as the description proceeds, the invention comprises the various novel features of construction and arrangement of parts which will be more fully described herein and set forth with particularity in the claims appended hereto.

Reference is had to the accompanying drawings forming a part of this application, in which like reference characters indicate the corresponding parts throughout the several views, in which—

Figure 1 represents an end elevation of the external terminal of the improved spark plug,

Fig. 2 represents an end elevation of the internal terminal of the plug,

Fig. 3 represents a longitudinal sectional view through the plug,

Fig. 4 represents a perspective view of the relatively adjustable electrode detached, and

Fig. 5 represents a detail sectional view through the support for one terminal of the adjusted screw.

Referring to the drawings in detail wherein similar reference numerals designate corresponding parts throughout the several views the numeral 5 indicates the hollow cylindrical body of the plug which is of such external shape and size as to be received in the port ordinarily formed in the wall of the explosive engine cylinder and which is provided with an integral circular

flange 6 provided with bolt holes 7 whereby the plug is rigidly secured and positioned upon the engine cylinder.

As in the ordinary construction of spark plugs, the body 5 consists of metal or other conducting material having requisite strength to withstand the explosions in the explosive chamber of the engine cylinder and a longitudinal opening 8 is formed in spaced parallel relation to the longitudinal axis of the body and pivotally receives the shank 9 of the relatively adjustable electrode 10 the inner terminal of which is enlarged to provide a shoulder 11 lying in contact with the inner terminal of the plug 5 to provide a fluid tight joint and the opposite terminal of the shank is externally threaded and receives a spacing element 11^a and securing nut 12. In order to establish a non-rotatable connection between the spacing element 11^a and the electrode shank 9 a portion of the latter lying inwardly of the external screw threads is preferably of polygonal form and indicated at 13 in Fig. 4 and an indicating member 15 is non-rotatably mounted upon the polygonal portion intermediate the spacing element 11^a and the nut 12 and is removable and rigidly held in position by the latter.

The extremity of the enlarged terminal of the electrode is directed angularly and provided with a sparking pin or point 16 arranged adjacent the insulated point 17 carried by the electrode 18 which latter is supported in a longitudinal opening in the body 5 disposed in spaced parallel relation to the opening receiving the shank 9 and having interposed between the electrode and the metallic body a wrapping of mica or other insulating material 19 and a tube of porcelain 20. The inner terminal of the electrode 18 is formed with a head 21 and external shoulder 22 limiting the movement of the electrode in one direction longitudinally of the body 5. The head 21 is partially cut away at the side from which the point 17 projects. The opposite terminal of the electrode is externally screw threaded and is received by a nut 23 by which the contact member 24 is electrically connected with the electrode and is adapted to be connected with one of the conductors of the ignition system of the engine in the usual manner.

The outer terminal of the indicating member 15 is enlarged and of circular form and is received between the terminal flanges 25

of an adjusting sleeve 26 having an internally threaded bore fitted upon the screw 27 which latter is mounted in angular brackets 28 bolted or otherwise secured to the flange 5 of the body 5 and suitably held against rotary movement with relation thereto. The extreme terminal of the indicator 15 is provided with a pointer 29 movable over a series of graduated marks 30 on the terminal of 10 the body and by which the length of the spark gap between the points 16 and 17 may be readily determined while the plug is in actual operation upon the engine.

In operation, the length of the spark gap 15 for electrical currents of varying intensity is determined by practical experiment and by using such experiments as a basis, the points may be set so as to obtain the best results with an electrical current of known 20 intensity. The proper adjustment of the relatively movable electrode or sparking point 16 is effected by rotary movement of the sleeve 26 upon the screw 27 thus causing the sleeve to move in either one direction 25 or the other effecting an oscillatory movement of the shank 9 in the body 5 and movement of the sparking point 16 toward or away from the point 17 according to the direction of movement of the sleeve 26.

30 The flanges at the terminals of the adjusting sleeve 25^a are preferably of polygonal form so as to be engaged by a suitable type of wrench for convenience in adjusting the sleeve longitudinally of the screw 27 and 35 the pins 16 and 17 are also preferably removably secured in position in order that they may be conveniently and inexpensively

removed and replaced by new ones, if necessary, or cleaned.

What we claim is:

40 1. A spark plug including a body, a sparking point electrically connected therewith and adjustably supported thereon, a relatively stationary sparking point insulated from the body, an indicating member carried by the relatively adjustable sparking member and provided with a circular terminal, a relatively stationary screw carried by the body, and a sleeve mounted for adjustment upon said screw and having terminal flanges confining the circular portion 45 of the indicating member for effecting adjustment of the latter simultaneously with the movement of the sleeve.

50 2. A spark plug including a body, a sparking point electrically connected therewith and adjustably supported thereon, a relatively stationary sparking point insulated from the body, a scale on said body, an indicating member carried by the relatively 55 adjustable sparking member movable across the scale, said indicating member having a circular enlarged portion, a relatively stationary screw carried by the body, a sleeve fitted upon the screw and adapted for adjustment thereon, and terminal flanges carried by the sleeve receiving the circular portion 60 of the indicating member for adjusting the latter over the scale.

65 In testimony whereof, we affix our signatures hereto.

DONALD W. LANG.
ARTHUR D. VAUGHN.
